UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

PANTOGRAPH.

Application filed April 25, 1924. Serial No. 708,895.

To all whom it may concern:

Be it known that I, WILLIAM SCHAAKE, a citizen of the United States, and a resident of Pittsburgh, in the county of Allegheny and State of Pennsylvania, have invented a new and useful Improvement in Pantographs, of which the following is a specification.

My invention relates to pantograph structures for electric railway vehicles and more particularly to the operating mechanism for raising and lowering the current-collector shoes that are carried by the pantograph structure.

It is among the objects of my invention to provide a pantograph structure in which the main actuating mechanism for raising the pantograph frame is supplemented by an auxiliary actuating means that functions to initially raise the pantograph frame.

It is a further object of my invention to provide an auxiliary device for operating the pantograph which shall also function as a buffer when the pantograph is lowered to an inoperative position.

It is a still further object of my invention to provide a pantograph structure and actuating means therefor which shall be of simple, compact and durable mechanical construction and which shall function efficiently in its operation to provide a quick-acting starting device for extending the pantograph frame.

Pantograph supports for current-collector shoes are constructed to facilitate raising or lowering the shoes relative to the overhead line structure, and the main actuating means utilized for the operation of the pantograph may be of any suitable type which most readily adapts itself to the control of the operator.

It has been well established in practice that fluid-pressure control and actuating means is best adapted for pantograph operation. However, by reason of the nature of the pantograph, there is an unavoidable dead center position, which is detrimental to efficient operation because of sluggishness and slow response when it is desired to extend the pantograph. It sometimes happens that the pantograph drops below the dead center position, in which case it is necessary to climb upon the vehicle and raise the panto-

graph up beyond the dead center position before it can be extended.

My present invention is directed to a fluid-pressure system which is adapted to be utilized in conjunction with an auxiliary fluid-pressure actuating mechanism that will obviate the difficulties heretofore encountered, relative to the dead center position of the pantograph, and further provide a quick starting means for initiating the movement of the pantograph before the primary extension means is actuated. This mechanism also functions as a buffer for the pantograph when lowered, thus eliminating possible damage to the operating parts.

In the accompanying drawings constituting a part hereof and in which like reference characters designate like parts:

Figure 1 is a plan view of a pantograph structure embodying the principles of my invention,

Fig. 2 is an end elevational view thereof,

Fig. 3 is a view, partially in side elevation and partially in cross-section, of the actuating means therefor,

Fig. 4 is a diagrammatic view thereof showing the fluid-pressure system,

Fig. 5 is a similar view illustrating the arrangement and co-ordination of the several co-operating parts, and

Fig. 6 is a view in cross-section of a diaphragm utilized in the fluid-pressure system.

Referring to Fig. 1, the device therein illustrated comprises a supporting structure embodying a plurality of parallel L-shaped or angle members 1, which are secured together by transverse supporting members 2 and 3, the end members 2 being mounted on suitable insulators 4 on the roof 5 of a railway vehicle. A pair of shafts 6 are disposed transversely of the structural members 1 and are rotatably secured thereto by bearings 7. The ends of the shafts 6 are provided with cranks 8, which are interconnected by crossed links 9 so that the rotation of one shaft member will produce an equal rotation of the other member. A pantograph structure 10 is secured to the shafts 6 and to a pair of current-collector shoes 11 which are connected by reinforcing strips or castings 12 that are secured to the upper frame portions of the pantograph.

A crank shaft 13 is disposed parallel to

the shafts 6 and is provided with cranks 14, which are disposed in the slotted openings 15 of a pair of cylinders 16. The cylinders are provided with pistons 17 that are adapted to engage the cranks 14. The crank shaft 13 is connected to the shafts 6 so that when the former is rotated, the shafts 6 will be actuated and thereby effect an extension of the pantograph structure 10.

10 The cylinders 16 are connected to a fluid pressure system as shown in Figs. 4 and 5, which comprises a pipe line 18 leading to a suitable source of fluid pressure having a connection 19 with the cylinders 16. One of 15 the cylinders is connected to a pipe line 20 leading to a pair of vertical buffer cylinders 21 by a pipe connection 22, Fig. 5. The cylinders 21 are provided with pistons 24 which are disposed underneath the castings 12 connecting the upper frame portions of the pantograph.

An air reservoir 25 is also connected to the pipe line 20, and a standard union 26 with a diaphragm having a relatively small opening is provided in the joint of the T 27 of the pipe line 20 and the connecting pipe 22 of the cylinder 16.

The operation of my device is briefly as follows: After the air or other fluid pressure is permitted to flow in the supply pipe 18, it will pass to the cylinders 16 through the connecting pipes 19 and also through the constricted opening of the diaphragm in the union 26 into the buffer cylinders 21 and the reservoir 25. The pantograph, being always sluggish in its collapsed position, is given a quick starting action or impulse by means of the auxiliary pistons 24, which impulse is augmented by the pressure exerted on the cranks 14, Fig. 3, by the pistons 17 of the air cylinders 16, thus raising the pantograph from a collapsed to an extended position.

If it is desired to lower the pantograph, the air or other fluid pressure, is exhausted from the pipe line 18 and the cylinders 16, but the escape of air from the pipe line 20 leading to the buffer cylinders 21 is retarded by the diaphragm 30 in the union 26. The residual air in the buffer cylinders 21 and the reservoirs 25 offers an excellent buffer effect to the dropping pantograph, permitting it to rebound and drop to its collapsed position without exerting any detrimental shock or impact on the mechanism and its support.

It is evident from the foregoing description of my invention that the means for operating the pantograph provides a quick raising action and an adequate buffer effect for the pantograph structure, which is highly desirable in the efficient operation of such a current-collector device and which greatly enhances its serviceability.

Although I have described a specific embodiment of my invention, it will be obvious

to those skilled in the art that various modifications may be made in the details of construction and the design and proportion of the several co-operating parts without departing from the principles herein set forth. 70

I claim as my invention:

1. In a pantograph trolley structure, the combination with a primary actuating mechanism, of an auxiliary device adapted to initiate the movement of the pantograph 75

2. In a pantograph trolley structure, the combination with an operating mechanism for actuating the pantograph frame, of means for effecting a quick-raising action. 80

3. In a pantograph trolley structure, the combination with an operating mechanism for actuating the pantograph frame, of means for effecting a quick-raising action, 85 said means comprising a fluid-pressure system.

4. In a pantograph trolley structure, the combination with an operating mechanism for actuating the pantograph frame, of means for effecting a quick-raising action 90 and a resilient retarding action.

5. In a pantograph trolley structure, the combination with an operating mechanism for actuating the pantograph frame, of means for effecting a quick-raising action 95 and a buffer action.

6. In a pantograph trolley structure, the combination with an operating mechanism for actuating the pantograph frame, of means for effecting a quick-raising action 100 and a buffer action comprising a fluid-pressure system including a reservoir and a pair of piston members.

7. In a pantograph trolley structure, the combination with an operating mechanism 105 for actuating the pantograph frame, of means for effecting a quick-raising action and a buffer action comprising a fluid-pressure system including a reservoir, and a pair of piston members and means for retarding the pressure of said system.

8. In a pantograph trolley structure, the combination with a fluid-pressure operating mechanism for actuating the pantograph frame, of a plurality of piston members and 115 means for restricting the flow of pressure between said operating mechanism and said pistons.

9. In a pantograph trolley structure, the combination with a fluid-pressure operating 120 mechanism for actuating the pantograph frame, of a reservoir and a plurality of piston members and a diaphragm for restricting the flow of pressure between said operating mechanism and said reservoir and pistons.

10. In a pantograph trolley structure, the combination with an operating mechanism for raising the pantograph frame, of means 125 for initiating movement of said structure. 130

11. In a pantograph trolley structure, the combination with a pantograph frame having collector shoes mounted thereon, of a fluid-pressure operating mechanism therefor comprising a plurality of fluid-pressure operable pistons and cylinders therefor, and a reservoir connected to said cylinders, certain of said pistons being adapted to initi-

ally engage the collector shoes, and means for restricting the flow of pressure between some of said cylinders and said reservoir.

In testimony whereof I have hereunto subscribed my name this 17th day of April 1924.

WILLIAM SCHAAKE.
